CLAIM

The ornamental design of a faucet assembly with sensor, as shown and described.

DESCRIPTION

FIG. 1 illustrates a perspective top view of a faucet assembly with sensor in accordance with the invention;

FIG. 2 illustrates a front view of the faucet assembly with sensor of FIG. 1;

FIG. 3 illustrates a right side view of the faucet assembly with sensor of FIG. 1;

FIG. 4 illustrates a left side view of the faucet assembly with sensor of FIG. 1;

FIG. 5 illustrates a bottom view of the faucet assembly with sensor of FIG. 1; and,

FIG. 6 illustrates a top view of the faucet assembly with sensor of FIG. 1.

The broken lines shown in the drawings represent unclaimed portions of the faucet and forms no part of the claimed design.
